ATTORNEY

UNITED STATES PATENT OFFICE.

WILLIAM G. CANFIELD, OF ST. LOUIS, MISSOURI.

WINDOW REFRIGERATOR.

Application filed April 18, 1922. Serial No. 554,621.

To all whom it may concern:

Be it known that I, WILLIAM G. CANFIELD, a citizen of the United States, residing at St. Louis, in the county of St. Louis 5 City and State of Missouri, have invented new and useful Improvements in Window Refrigerators, of which the following is a specification.

This invention relates to a window refrigerator, and the object is to provide a cabinet or the like to be applied to the inner side of a window sash, and so constructed that the outside temperature or nearly that temperature will be maintained in the 15 cabinet.

A further object is to provide a device of this type having one open side and insulated walls on the remaining sides with means for effecting air tight contact with 20 the surface of the glass in the window sash, so that the air within the cabinet will be maintained at substantially the temperature of the outer air and of the glass unaffected by the temperature of the room in which the 25 cabinet is located.

A still further object is to provide a cabinet of this character with particular means for permitting access to the interior, and particular mounting means.

With the foregoing and other objects in view, the invention consists in the novel construction and arrangement of elements described and claimed, it being understood that modifications may be made within the 35 scope of the claims without departing from the spirit of the invention.

In the drawings, Figure 1 shows the refrigerator in front elevation; the window sash and glass on which it is mounted being broken away; Figure 2 is a horizontal section through the structure of Figure 1; Figure 3 is a vertical section through the lower element of the sash, and a portion of the bottom of the refrigerator; Figure 4 is a 40 section through a combined ventilating and securing device; Figure 5 is a fragmentary section showing modified mounting means.

The cabinet includes side walls, top and 50 bottom walls, and a front wall, all of these elements being double and providing an interior air space, for insulation.

The outer side walls are designated 10 and 12, and the corresponding top and bottom walls are shown at 13 and 14, the front 55

wall of the outer structure being designated 15.

The inner walls, spaced from said outer walls form the inner structure shown at 16. The air chamber, affording insulation is designated 18, and extends between all side walls correspondingly located, and the various other walls of the cabinet.

Gaskets 19 and 20 are located in grooves 21 and 22, in the edge portions of the wall, 60 these gaskets effecting air tight connection with the glass of the window sash.

Connecting and supporting rods 25 and 26 extend vertically through the cabinet walls, and lugs or nuts, such as at 27, are 65 threaded onto the rods, at the points shown and contacts with the adjacent elements of the cabinet.

Openings are provided in the front walls of the inner and outer receptacles, and these 70 openings are closed by doors 30 and 31, mounted on spring hinges 32 and connected by a link 33, so that both doors open at the same time. The door frames are designated 34 and 35.

Outside air may be admitted to the interior, when desired, by passing a tube 5 through the window sash, or frame, and connecting this tube with the entrance to a bore drilled through one or more of the 80 rods, the bore opening within the cabinet.

The bottom of the box or cabinet rests on the lower element of the sash. Brackets 36 and 37 are secured to the frame of the sash and carry springs 38 and 39, each bearing 90 on one of the rods and holding the cabinet in positive contact with the surface of the glass.

It is intended that the outer surface of the cabinet shall have a natural wood finish, 95 and that the inner wall of the cooling chamber shall be enameled.

The inner receptacle with its lining 16' may be removed, if desired, by detaching the air connections. Figure 4 shows an upper vent 26', and it should be added that one or more of the air connections may open 100 into chamber 18.

In the modified form of Figure 5, I have shown an angular resilient metallic element 105 41, held in position by short rods or bolts 42 and supporting the lower portion of the outer receptacle. One flange of this angular member extends into the lower element of the sash in the position shown, and be- 110

tween the glass 43 and the sash element 44. The parts are so formed and proportioned that the edges of the receptacle or receptacles are in close contact with the surface of 5 the glass.

Having thus described the invention, I claim:

1. In a device of the class described, a receptacle formed with inner and outer spaced 10 walls providing an intermediate air chamber and an inner chamber having one open side, means for mounting the receptacle in contact with the glass of a window sash, the mounting means including resilient devices 15 and securing elements, one of which is tubular, for placing the inner air chamber in communication with the outside air.
2. In a device of the class described, a

receptacle formed with inner and outer spaced walls providing an intermediate air 20 chamber and an inner chamber having one open side, means for resiliently mounting the receptacle in contact with the glass of a window sash, said mounting means including brackets mounted on the sash and 25 springs connected with the brackets, rods passing through the walls of the receptacle and threaded devices carried by the rods, the springs engaging the end portions of said rods for retaining the receptacle in position, one of said rods being tubular and admitting air to the receptacle. 30

In testimony whereof I affix my signature.

WILLIAM G. CANFIELD.
